COLOR LIGHT PROJECTING MACHINE

John Venetta, Warren, Ohio

Application October 31, 1938, Serial No. 238,050

2 Claims. (Cl. 240—3.1)

This invention relates to color light projecting machines, and has for the primary object the provision of a device of this character which may be easily made to project light rays over a comparatively large area and to project or concentrate light rays onto a restricted area much in the form of a spotlight and with the larger area still illuminated thereby if desired.

Another object of this invention is the provision of means for varying the color of the light rays with the colors continuously changing when desired and to have the light rays of a selected color as long as desired.

A further object of this invention is the provision of means whereby the machine may be turned to the right and to the left and also moved in upward and downward directions so that the light rays may be brought onto various selected areas.

With these and other objects in view, the invention consists in certain novel features of construction, combination and arrangement of parts to be hereinafter more fully described and claimed.

For a complete understanding of my invention, reference is to be had to the accompanying drawings and following description.

In the drawings:

Figure 1 is a vertical sectional view illustrating a color light projecting machine constructed in accordance with my invention.

Figure 2 is a vertical sectional view showing one of the light housings and the means of focussing the light therein.

Figure 3 is a detail sectional view taken on the line 3—3 of Figure 2.

Figure 4 is a transverse sectional view showing a pair of light housings and their mounting on a main supporting disc.

Figure 5 is a transverse sectional view illustrating one of the light housings, with the electric lamp therein mounted for manual adjustment.

Figure 6 is a plan view illustrating a contact disc.

Figure 7 is a front elevation illustrating a color screen.

Figure 8 is a top plan view illustrating key type switches mounted in a single unit for controlling the electric circuit of the device.

Figure 9 is a sectional view taken on the line 9—9 of Figure 8.

Figure 10 is a diagrammatical view illustrating the wiring diagram.

Referring in detail to the drawings, the numeral 5 indicates a supporting bracket mounted

on a wall or any other suitable support by fasteners 6 and journaled in the bracket 5 adjacent the free end thereof is a vertically arranged shaft 7 and has pivoted to its lower bifurcated end 8 a lug 9 forming an integral part of a bracket 10 5 acting as a support for a vertically arranged disc 11.

The disc 11 at opposite sides thereof is provided with openings in which are mounted lenses 12 and mounted on the rear face of the supporting disc 11 and in alignment with the lenses 12 are lamp housings 13 and 14 similarly constructed and each having one side thereof in the form of a hinged door 15 held in a closed position by a fastener 16. The purpose of the doors is to give access to the lamp housings for examining electric lamps 17 therein. The doors 15 and the walls of the lamp housings opposite to said doors are provided with ventilating openings 18. The electric lamps 17 are mounted in electric lamp sockets 19 mounted on slides 20. The slide 20 of the electric lamp socket of the housing 14 carries a bolt 21 extending through a slot in the bottom wall of said housing 14 to receive thereon a wing nut 22 for securing the electric lamp 17 25 15 to various adjusted positions with respect to the lens associated therewith. The wing nut and bolt permit the electric lamp 17 of the housing 14 to be manually focussed.

The slide 20 of the housing 13 has a headed 30 fastener 23 operating in a slot in said housing 13 whereby the slide may be slid freely in an end-wise direction within the housing so as to vary the electric lamp carried thereby with respect to the lens of said housing 13. The adjustment 35 of the lamp in the housing 13 permits focussing of the light rays through the lens of said housing and to concentrate the light rays on a restricted area when desired. The light rays from the electric lamp of the housing 14 preferably 40 cover a comparatively larger area. A power means is provided for the focussing of the lamp 17 in the housing 13 and which will be hereinafter more fully described.

The slide 20 in the housing 13 carries a pin 24 45 on which is mounted a feed nut 25. Engageable with opposite sides of the feed nut 25 are coil springs 26 and threaded in the feed nut is a feed shaft 27 extending exteriorly of the housing 13 and is geared to an electric motor 28 of the reversible type. Through the use of the electric motor 28 the slide 20 may be caused to move in opposite directions in the housing 13 for the purpose of focussing the lamp 17 therein by power means.

Arranged in opposite ends of the housing 13 are circuit breakers 29 the purpose of which is to break the electric circuit to the electric motor 28 when the slide 20 reaches the limit of its movement in the housing 13 in either direction. The circuit breakers 29 each consists of a jack including contact members 30, 31 and 32. The contact members 31 and 32 are normally in engagement with each other and the contact member 31 is longer than the contact member 32 to be engaged by an extension 33 carried by the slide when the latter reaches the limit of its movement in an endwise direction. An insulating block 34 is carried by the contact 30 and engages the contact 31 to normally space the contact 30 from the contact 32. The tendency of the contact 30 is to engage with the contact 32, however, it is held disengaged therefrom by the block 34 engaging the contact 31. The circuit breakers 29 each described in detail will be again referred to in the electric circuit.

A device 35 for varying the color of the light rays projected through the lens 12 by the electric lamps 17 is rotatably mounted in front of the supporting disc 11 and consists of a disc-like frame including a plurality of removable sections 36 for supporting screens 37 of different colors, as clearly shown in Figure 7. During the rotation of the device 35 the various screens pass the lenses 12. The device 35 is secured on a shaft 37' journaled in the supporting disc 11 and suitably connected to an electric motor 38 by a reduction gearing of a conventional construction and located in a casing 39. The electric motor in the casing 39 is supported by a shelf 40 mounted on the bracket 10 and the supporting disc 11. The purpose of the motor 38 is to rotate the device 35 to bring the various color screens opposite the lenses 12 of the light housings 13 and 14.

40 The supporting disc 11 is constructed of insulating material and mounted thereon is a plurality of contact fingers 41, there being a contact finger 41 for each of the screens, and said contact fingers bear on a contact disc 43 mounted on the 45 shaft 37'. The contact disc 43 is of an electric conductive material and arranged therein is a non-conductive member 44 to be engaged by the contact fingers during the rotation of the disc 43 for the purpose of breaking an electric circuit 50 which will be hereinafter more fully described. The contact disc 43 is engaged by a brush type contact 46. The contacts 41 and 46 are connected in the electric circuit of the motor 38 and as this circuit is manually controlled through a series of 55 switches which will be hereinafter more fully described, the electric motor 38 may be made to operate the device 35 so that any selected screen may be brought opposite a lens 12.

60 An electric motor 47 of the reversible type is suitably mounted on the shaft 7 and is connected to a crank shaft 48 through gears 49 and the crank of said crank shaft is connected to a link 59 which is in turn pivoted on the supporting disc 11. By operating the motor 47 in opposite directions the supporting disc 11 and the lamp housing carried thereby as well as the device 35 will be caused to move upwardly and downwardly and the pivot between the lug 9 and the shaft 7 65 70 acting as the axis of movement.

An electric motor 51 of the reversible type is mounted on the bracket 5 and by gearing means 52 is connected to the shaft 7 for the purpose of rotating said shaft in opposite directions which will bring about turning of the supporting disc 11.

and the parts carried thereby to the right and to the left.

A switch mechanism of the manually operated type is employed for controlling the circuits of the electric motors 33, 28, 47, and 54 and the electric lamps 11 and is indicated in entirety by the character 54 and consists of a suitable casing 55 having mounted thereon master switches 56 and 57 and a plurality of key type switches 58, 59, 60, 61, 62, 63, 64, 65, 66, 67, 68 and 69. Also mounted in the casing 55 are contact bars 70 and 71 suitably insulated from each other and operating between said bars are the key type switches 58 to 63, inclusive, said key type switches being mounted on a suitable support 72 in the casing and normally are in engagement with the contact bar 70, as clearly shown in Figure 9, and may be manually moved into engagement with the contact bar 71.

By referring to Figure 10 it will be seen that 20
the key type switches 52 to 63 are always in en-
gagement with the contact bar 76 and the latter
is shorter in length than the bar 74 and the key
type switches 54 to 66 do not engage with the con-
tact bar 76 but may be moved manually into en- 25
gagement with the contact bar 74.

The main electric leads or conductors are indicated by the characters 73 and 74. The conductor 74 is electrically connected to the motors 51, 47, 28 and 38. The conductor 73 is connected to 30 the master switches 56 and 57 and also connected to the contact bar 71. A conductor 75 connects the switch 56 to one of the electric lamps 17 and a conductor 76 connects the switch 57 to the other electric lamp 17. The electric lamps 17 are connected to the conductor 74 by a conductor 77. A conductor 78 connects the contact bar 70 with one side of the reversible motors 51, 47 and 28 and also is connected to the circuit breakers 29 shown associated with the reversible motor 28 in Figure 40 10. One of the circuit breakers 29 is connected to the key type switch 62 by a conductor 79 and the other circuit breaker 29 is connected to the key type switch 63 by a conductor 80. The circuit breakers 29 are connected to the opposite side of 45 the motor 28 from the conductor 74 by conductors 81.

Conductors 82 and 83 connect the key type switches 69 and 64 to the reversible motor 47 and conductors 84 and 85 connect the key type switches 58 and 59 to the reversible motor 50.

The brush type contact 43 is connected to the conductor 14 through the motor 39 by a conductor 89. The key type switches 64, 65, 66, 67, 68, and 69 each have a contact 44 connected thereto by conductors 87.

In operation, it is to be understood that the master switches 56 and 57 are closed which illuminate the electric lamps 17. When the master switches are closed the flow of electricity will be 60 through the switches 58 and 59 from the conductor 73 through the conductors 75 and 76 to the electric lamps and from the latter to the conductor 74 by way of the conductor 71. When it is desired to turn the machine to the right and 65 to the left the key type switches 58 and 59 are alternatively depressed which brings about a reverse operation of the electric motor 51. When it is desired to move the machine to the right, for instance, the key type switch 58 is depressed 70 and the flow of the current is then from the conductor 73 through the bar 71, key type switch 58, conductor 84, through the motor 51, conductor 85 through the key type switch 59, bar 70 and conductor 78 to the conductor 74 through the oppo- 75

site side of the reversible motor 51. When it is desired to turn the motor to the left the key 59 is depressed and the flow of the current is then from the conductor 73 through the key type switch 59, conductor 58, through one side of the motor 51, conductor 84, key type switch 58, through the bar 70 then through the conductor 78 to the conductor 74 through the opposite side of the motor 51.

10 When it is desired to move the machine upwardly and downwardly the key type switches 60 and 61 are alternately depressed and when the key 60 is depressed the flow of the current is then from the conductor 73 through the bar 71, key type switch 60, conductor 82, through the motor 47 and through the conductor 83 to the key type switch 61, then to the bar 70 to the conductor 78 and from the latter to the conductor 74.

20 When it is desired to operate the motor 47 in a reverse direction the key type switch 61 is depressed engaging the bar 71 so that the flow of the current will be from said bar through said key type switch 61, conductor 83, electric motor 25 47 and conductor 82 to the key type switch 60 and then through the bar 70 to the conductor 78 and from the latter to the conductor 74.

The reversing of the motor 28 is through the alternate depressing of the keys 62 and 63 and 30 when the slide 20 of the lamp housing reaches the limit of its sliding movement in one direction one of the circuit breakers 29 will stop the motor 28 and when the slide reaches the limit of its movement in an opposite direction the other circuit breaker 29 will break the circuit to the motor 28.

It is preferable that the key type switches 64 to 69, inclusive, be colored in accordance with the screens 37 which they control so that, for instance, if the key type switch 63 is of a blue color 40 the screen which it controls will be of a corresponding color. For instance, if the key type switch 64 is moved in engagement with the bar 71 the blue screen will be brought into a position opposite the lens 12 of the light housing 13 while 45 the screen diametrically opposite thereto will be positioned over the lens 12 of the light housing 14. When the key 64 for instance is depressed in engagement with the bar the flow of the current will be from the conductor 73 through the bar 50 71, key type switch 64, conductor 87 connected thereto and to one of the contacts 41, then through the contact disc 43 to the brush contact 46 and from the latter through the conductor 86 to the motor 38 and from the latter to the conductor 74. The depressing of the key type switch 55 64 sets the motor 38 in operation and when the contact connected to said key type switch 64 comes into engagement with the insulated member 44 on the contact disc 43 the circuit to the electric motor 38 will be broken, bringing the desired screen opposite the lens of the light housing 13. The control of the other colored screens is through the operation of the other key type switches 65 to 69 in accordance with that described in connection with the key type switch 64. Thus it will be seen that any one of the colored screens can be brought in position in front of the lens 12 of the light housing 13 while the colored screen opposite thereto will be positioned in front of the lens 12 of the light housing 14. When it is desired to bring about a continuous rotation of the colored screens in front of the lenses of the light housings 13 and 14, the keys 64 to 69 are simultaneously depressed.

From the foregoing description when taken in connection with the accompanying drawings, it will be seen that a very simple and efficient color projecting machine has been provided which is easy to mount and easy to control, permitting the light rays therefrom to be directed onto selected areas as desired and with the light rays from one of the electric lamps concentrated or restricted to a smaller area when desired through the operation of the focussing electric motor which controls and operates the focussing position of the electric lamp in the housing 13. Further it may be seen that any selected color screen may be brought in front of the lenses of the housing 13 when desired and the various colored screens 15 may be made to rotate continuously in front of the lenses of the light housings 13 and 14 to provide a varying or color changing effect on the areas illuminated by the device. It further will be seen that this device can be conveniently and 20 easily controlled from a remote point to its place of location through the operation of the master switches 57 and 56 and the key type switches 58 to 69, inclusive.

This application is a continuation in part of my application Serial No. 179,359 filed December 11th, 1937 and abandoned November 7, 1938.

It is believed that the foregoing description, when taken in connection with the drawings will fully set forth the construction and advantages of this invention to those skilled in the art to which such a device relates so that further detailed description will not be required.

Having described the invention, what I claim is:

1. A color light projecting machine comprising a disc having spaced lens openings, a bracket secured to and projecting from one side of the disc, lenses carried by the disc in alignment with the openings and located at opposite sides of the bracket, lamp housings located at opposite sides 40 of the bracket and carried by the disc with the lenses located therein, lamps adjustably mounted in the housings and adjustable toward and from the lenses, a rotatable color screen located in advance to the disc and the openings thereof, a shaft pivoted on the bracket and extending vertically between the lamp housings, a wall bracket rotatably supporting the shaft, means for rotating the shaft in either direction and supported by the wall bracket, and means supported by the 50 shaft and connected to said disc for pivoting the first bracket on the shaft in opposite directions.

2. A color light projecting machine comprising a disc having spaced lens openings, a bracket secured to and projecting from one side of the disc, lenses carried by the disc in alignment with the openings and located at opposite sides of the bracket, lamp housings located at opposite sides of the bracket and carried by the disc with the lenses located therein, lamps adjustably mounted 60 in the housings and adjustable toward and from the lenses, a rotatable color screen located in advance to the disc and the openings thereof, a shaft pivoted on the bracket and extending vertically between the lamp housings, a wall bracket rotatably supporting the shaft, an electric power means supported by said wall bracket and geared to the shaft for rotating the latter in opposite directions, a power shaft including a crank supported by the first-named shaft, a link pivoted 70 to the crank and to the disc, and a power means supported by the first-named shaft and geared to the power shaft.

JOHN VENETTA.
